Almon A. Johnson, Superior, Wis., assignor to
Superior Iron Works Company

Application June 22, 1931. Serial No. 546,017

13 Claims. (Cl. 254—172)

My invention relates to winches, and has for its object the provision of a simple, compact, durable and efficient reversible winch, capstan, or the like, adapted to automatically overhaul, or 5 pay out a towing, hauling, or mooring line, or cable, when the strain thereon is reduced or increased beyond a predetermined tension. It has for a further object the provision of a winch of the character referred to which may also be 10 arbitrarily operated. With these and other objects in view, it consists of the structures, combinations, and arrangements of parts hereinafter described and claimed.

In the drawings, Fig. 1 is a section of my invention approximately on the line 2—2 of Fig. 3. Fig. 2 is a section of said invention approximately on the line 1—1 of Fig. 1, partly broken away and omitting the motor and train of gears between the motor and drum shaft hereinafter referred to. Fig. 3 is a side elevation of said invention. Fig. 4 20 is an enlarged rear elevation of an operating lever, locking quadrant and fragment of a rock bar. Fig. 5 is an enlarged side elevation of said operating lever and quadrant, and of a latch for said lever. Fig. 6 is a fragmentary elevation of 25 two pivotally connected levers, one of them being in section on the line 3—3 of Fig. 1.

Fig. 7 is an enlarged central horizontal section of a modified form of controller. Fig. 8 is an enlarged vertical section of said modified form of controller, on the line 4—4 of Fig. 7. Fig. 9 is a top plan view of a modified form of prime mover. Fig. 10 is a schematic view of the interior of the preferred electric controller and electric switch panel, showing also an electric motor and dynamic 30 brake. Fig. 11 is a top plan view of a gear 5 (shown in Fig. 1) and of transmission means between a modified form of prime mover (shown in Fig. 9) and said gear.

In the drawings, 1 is a base of any suitable form 40 or structure. Journalled in any suitable bearings on said base, as 1^a, 2^a, is a drum shaft 2, upon which is mounted a gear 3, adapted to rotate said shaft and to be driven by any suitable engine or prime mover, as by an electric motor 4, or by a steam engine 50, preferably through a train of speed reducing gears, as 5^a and 6.

Loosely mounted on said shaft, is a cable drum member 7. Loosely mounted on said shaft is also 50 a brake wheel member 8, provided with a flange 8^a, upon which is mounted a brake band 8^b. Keyed to said shaft and adapted to be rotated thereby is a sun gear 9. Journalled upon one of said members are one or more planetary gears 55 adapted to engage said gear 9, and to engage an

internal gear formed upon the other of said members, as planetary gears 10, 11 and 12 preferably journalled upon one end of said drum and adapted to engage said gear 9, and an annular internal gear 8^c formed upon said brake wheel, by which 55 planetary gears said internal gear 8^c and said gear 9 are enabled to turn said drum. It will be observed, however, that when the prime mover and shaft 2 and gear 9 are idle and stationary said gear 9 forms a fixed fulcrum for the planetary 60 gears, which, if the drum be then rotated by the excessively strained cable will tend to rotate said brake wheel, or to slip said brake wheel with respect to said brake band. But before such slip can occur, said band, because of its frictional 65 engagement with said wheel, will be rocked a short distance by said wheel in opposition to the hereinafter described spring 21. Said movement of the band, or wheel, or both of them, will be communicated to any suitable devices for admitting 70

any suitable energy-creating means to the prime mover as through levers 24, 25, 26 and 27 to an electric controller 28 for admitting electric current from any suitable source, as a battery 28^a to an electric switch panel 28^b, which is connected 75 to said controller by a circuit wire cable 28^c, and to said motor 4 and brake 4^a by the circuit wire cable 28^d. Instead of said source of electricity, electric controller, circuit wires, electric motor

and dynamic brake, there may be substituted a 80 source of steam pressure as a boiler (not shown, but well known to the art), and a suitable reversing steam valve 51, adapted to communicate with said boiler through a pipe 58, and through pipes 51^a and 51^b with the steam chest 52 for the cylinder 53 of a steam engine 50; said valve being also 85 preferably adapted to communicate through pipes 51^c and 51^d with the steam chest 54 of the cylinder 55 of said steam engine 50; said steam engine 90 being adapted to drive said gear 5 by any suitable means or in any suitable manner, as by piston rods 53^a, 55^a; connecting rods 53^b, 55^b; crank arms 53^c, 55^c; a crank shaft 56; and a gear 57 keyed to said shaft 56 and adapted to engage said gear 5. The valve stems 53^d and 55^d of said engine 95 may be pivoted at their outward ends to eccentric collars 56^a and 56^b, respectively, journalled on said shaft 56. Thereupon said prime mover and intermediate gears will rotate said shaft 2, which will turn said gear 9, thus changing the character 100 of gear 9 from a fixed fulcrum for the planetary gears to a driving gear for said drum and changing the character of the brake wheel from a driven wheel to a stationary fulcrum dominated or fixed by said brake band. The drum will thus 110

be operated to pay out said cable rapidly until the excessive strain thereon is relieved, when, as will hereinafter appear, said motor will be stopped and said band will be retracted to normal position by said spring 21.

The ends of said brake band in the preferred form of my said invention are spaced from each other, and each of such ends is provided with an outwardly directed tongue, as 14 and 15, respectively, extending substantially parallel to and spaced from each other. Said band is contracted or set upon said wheel under predetermined primary pressure by any suitable resilient means provided with any suitable bearings. For example, at one side of such pair of tongues, a post 16 is erected upon said base. Extending loosely through both of said tongues, is a bolt 17, provided with a head adapted to bear against the outer face of the one of said tongues farthest from said post. A compression spring 18 and compression follower 19 and nut 20 are mounted upon said bolt between said post and the adjacent one of said tongues and spaced from said post, and a compression spring 21, and a compression follower 22 and nut 23 are mounted upon said bolt at the opposite side of said post with the forward end of said spring 21 bearing against said post, by means of which spring 18 said brake band is set at a predetermined primary tension upon said brake wheel, and by means of which spring 21, any rocking movement of the brake band and brake wheel in one direction is yieldingly resisted and limited. If desired to temporarily loosen said brake band 8^b in order to manually run the cable off the drum to towing or mooring length, the terminal nuts on the rod 17 may be retracted to release the tension on the springs 18 and 21, so that the brake wheel and drum will turn freely. If desired to omit said brake band, said rod 17 may be attached in any suitable manner directly to said wheel 8, as to a wrist pin 8^d thereon, instead of to the tongues 14 and 15; in such case, the spring 18 may be omitted, as will be readily understood.

Secured at one end to any suitable anchorage adapted to be moved by said wheel 8, as to a wrist pin 8^d on said wheel or, preferably, to one of said tongues, is a train of transmission devices of any suitable structure as, for example, a series of pivotally connected links or levers, 24, 25 and 26, which train is secured at its opposite end to a valve stem or controller lever for any suitable structure or type of prime mover, as to the controller lever 27 of a controller 28 of any suitable structure or type adapted to control the flow of power fluid or energizing means to such prime mover, and preferably to also govern a suitable brake for such prime mover; for example, to control the flow of electricity to said motor 4, and to govern any suitable form of magnetic or other electric brake, as 4^a.

Said lever 25 is pivoted intermediate of its ends, as at 25^a to one end of a transversely reciprocatable link 29 which is pivoted at its opposite end, as at 29^b, to a rock shaft 30, which rock shaft is mounted in any suitable bearings, as 30^a and 30^b, and is engaged at its opposite end by a manually operable lever 31 provided with any suitable locking means, as a latch 32 adapted to engage a locking quadrant as 33.

As has been observed, said spring 18 may be adjusted at any suitable constant primary tension to set said brake and hold said brake wheel against any suitable predetermined degree of strain on the towing or mooring line or drum, but that if

such strain is exceeded, the drum and brake wheel will tend to rotate and rock said wheel and brake band a short distance in opposition to said spring 21. Any movement of said wheel and band under such conditions will be communicated through said train of links to the controller which will close the circuit of said magnetic brake and close the circuit to said motor which will then through the train of intermediate gears rotate the drum and pay out said cable to relieve the excessive strain on the same. When said strain is relieved, said spring 21 will draw the brake band back to normal position, which motion will be communicated to said controller lever and cause it to cut off the current to said motor and to open the circuit of said magnetic brake. Said controller is also preferably adapted in any suitable manner and by any suitable means to vary the speed of said motor according to the degree of excessive strain on said cable. This is accomplished by the modified steam governed form of my invention by the controller valve operating to enlarge or reduce the open area of the steam ports according to the degree and direction of the oscillation of the brake wheel or brake band.

Any of various forms or arrangements of electrical operating means or control may be used in combination, or connection with said winch, in one form of which electrical means, 4 is an electric motor comprising an armature 4^d, a series field 4^b and a shunt field 4^c. Said controller 28 comprises an oscillatable drum, not shown, adapted to be rocked or oscillated by the crank lever 27. Mounted upon any suitable stationary supports adjacent to said drum are two groups of stationary contactors, one of which groups comprises the contactors 28^e, 28^f, 28^g, 28^h, and 28ⁱ, spaced from each other and from said drum and insulated from their support, said contactors being electrically connected together in any suitable manner as by a conductor wire or bar 28^j. The other said group is spaced and insulated from the first said group and comprises the contactors 28^k, 28^l, 28^m, 28ⁿ, 28° and 28^p, spaced from each other and insulated from their support and electrically connected with each other by the conductor wire or bar 28^m. Between said two groups is a group of movable contactors 60, 61, 62, 63, 64, 65, and 66, mounted on said drum and adapted to be moved thereby.

The contactor 60, is connected with said source 28^a in any suitable manner, as with the plus side thereof by the wire 28^r.

One of said stationary groups, as the group 28^e to 28ⁱ, inclusive, is termed the heaving-in group or side of the controller, three or more of the contactors thereof being in circuit during the heaving-in operation of said winch.

The other of said stationary groups of contactors as the group 28^k to 28^p, inclusive, is termed the paying-out group, or side of said controller, three or more of the contactors of the latter stationary group being in circuit during the paying-out operation of said winch.

When said drum is oscillated a sufficient distance in one direction, three or more contactors of the heaving-in group come into contact with respectively opposite contactors of said movable group. When said drum is rocked or oscillated in the opposite direction, four or more contactors of the paying-out group come into contact with respectively opposite contactors of the movable group. When the drum is at central or neutral position none of the contactors of the movable

- group is in contact with any of the contactors of either of said stationary groups.
- The movable contactor 61 is connected with the opposite side of said source as by a minus line wire 28^s and a branch wire 61^a, in which latter wire is interposed a solenoid coil 61^b, adapted to close a normally open relay 61^c, the coil being distant from said relay in the diagram to avoid confusion in connecting wires.
- 10 Said movable contactor 62 is connected with the minus side of said source through said line 28^s and a branch wire 62^a, in which wire 62^a is interposed a normally closed interlock circuit closer 62^b, a solenoid coil 62^c, adapted to close a normally open relay 62^d, and a solenoid coil 62^e adapted to close a normally open relay 62^f. The movable contactor of the interlock circuit closer 61^b is mounted upon the movable contactor of the relay 63^d, hereinafter referred to, and is adapted to open when said relay 63^d closes.
- 15 The movable contactor 63, is connected with the minus side of said source by said line wire 28^s and by a branch wire 63^a, in which latter wire is interposed a normally closed interlock circuit closer 63^b, a solenoid coil 63^c adapted to close a normally open relay 63^d, and a solenoid coil 63^e adapted to close a normally open relay 63^f. The movable contactor of said interlock circuit closer 63^b is mounted on the movable contactor of said relay 62^d and is adapted to be opened thereby when said relay 62^d closes.
- 20 Said movable contactor 64 is connected with the minus side of said source by said wire 28^s and a branch wire 64^a in which branch wire is interposed a solenoid coil 64^b adapted to open a normally closed contact 64^c which is normally held closed by a spring 64^d.
- 25 Said movable contactor 65 is connected with the minus side of said source by said wire 28^s and by a branch wire 65^a, in which wire 65^a is interposed a solenoid coil 65^b adapted to close a normally open relay 65^c.
- 30 Said movable contactor 66 is connected with the minus side of said source by said wire 28^s and a branch wire 66^a, in which wire 66^a is interposed a solenoid coil 66^b adapted to open a normally closed relay 66^c which is normally held closed by a spring 66^d.
- 35 Solenoid coils 67, 68, and 69 are connected in parallel with the plus side of said source by said wire 28^s.
- 40 Said coil 67 is adapted to close a normally open relay 67^a and is connected in parallel with the minus side of said source by electrically parallel wires 67^b and 67^c and by minus line wire 28^s. In said wire 67^b is interposed a normally open relay 67^d adapted to be closed by an interlock circuit closer 67^e which is mounted upon the movable contactor of said relay 62^f and is adapted to close when said relay 62^f closes. In said wire 67^c is interposed a normally open relay 67^f adapted to be closed by an interlock circuit closer 67^g which is mounted upon the movable contactor of said relay 66^c and is adapted to close when said relay 66^c opens.
- 45 Said coil 68 is adapted to close a normally open relay 68^a and is connected with the minus side of said source by a wire 68^b and by said wires 67^b and 67^c and said interlock circuit closers 67^e and 67^g and said wire 28^s. In said wire 68^b is interposed a normally closed jam relay 68^c the circuit closer of which is adapted to be retracted or opened by a solenoid coil 68^d when an overload occurs in the motor circuit.
- 50 Said coil 69 is adapted to close a normally open relay 69^a and is connected with the minus side of said source by a wire 69^b, said wire 68^b, said relay 68^c, said wires 67^b and 67^c, said normally open interlock circuit closers 67^e and 67^g and said wire 28^s. It will be observed that when said jam or overload relay opens, said relays 68^c and 69^a will be cut out of circuit, thus cutting into the motor circuit certain resistance elements 74, 73, and 72, hereinafter referred to.
- 55 The solenoid coils 70, 71, and 72 are holding coils for holding open the relays 67^a, 68^a and 69^a, respectively, which are open except when said relays are closed by the coils 67, 68, and 69, respectively, at which times said coil 70 is shorted by the closing of said interlock circuit closer 67^e or 67^g, and at which times said holding coils 71 and 72 are deenergized or shorted by the closing of relays 67^a and 68^a, respectively.
- 60 Resistance elements 75, 74, 73 and 72 are interposed in the main armature circuit until said elements 75, 74 and 73 are shorted out by the closing of the relays 67^a, 68^a and 69^a, respectively. Other resistance elements are inserted where necessary or advisable, as 76, 77, 78, 79 and 80. Manually operable switches or circuit closers as 81, 82, 83 and 84 are inserted wherever necessary or advisable.
- 65 In operation, the manually operable switches being closed, the shunt field 4^c is energized and holding coil 70 is energized. When the controller drum is turned to first heaving-in position, bringing the contactors 60, 61 and 62 into contact with the contactors 28^s, 28^t and 28^u, respectively, relay 61^c closes, releasing the brake 4^a; relay 62^d closes; relay 62^f closes; interlock 63^b opens; current flows through series field 4^b, relay 62^d; resistance elements 75, 74, 73 and 72, and simultaneously through the armature and resistance element 76, thence through relay 62^f to the minus side of the source; the motor turns slowly. Interlock circuit closer 67^e closes; relays 67^a, 68^a, and 69^a close, cutting out resistance elements 75, 74 and 73, and shorting the holding coils 71 and 72; the speed of the motor increases.
- 70 When the controller drum is turned in the same direction to second heaving-in position bringing the contactor 64 into contact with contactor 28^u, relay 64^c opens cutting out resistance element 76; the speed of the motor increases.
- 75 When the controller drum is turned farther in the same direction, bringing the contactor 66 into contact with the contactor 28^u, relay 66^c opens, cutting out the shunt field 4^c, and the motor runs at high speed. When the controller drum is reversed to central or neutral position, the relay 61^c opens and the brake 4^a is set by a spring. The motor—then running by momentum as a dynamo, the current generated thereby flowing through a circuit comprising the armature and said resistance element 76—slows down and stops.
- 80 When the controller drum is turned from neutral, to first paying-out position, bringing the contactors 60, 61, 63 and 65, into contact with the contactors 28^k, 28^l, 28^m, and 28^o, respectively, the relay 61^c closes releasing the brake 4^a; relays 63^d and 63^f close; interlock 62^b (mounted on the movable contactor of relay 63^d), opens, relay 65^c closes; current flows simultaneously through shunt field 4^c and series field 4^b, the relay 63^d, and simultaneously, or in parallel, through the armature and resistance elements 76 and 77, thence through resistance elements 72, 73, 74
- 85 35
- 90 90
- 95 100
- 100 105
- 110 115
- 115 120
- 120 125
- 130 135
- 140 145
- 145 150

and 75, and relay 67^a to the minus side of the source; the holding coils 70, 71 and 72 are energized; the motor turns slowly in paying-out direction.

5 When the controller drum is turned farther in the same direction, the contactor 65 passes beyond and out of contact with the contactor 28^a; the relay 65^c opens; the speed of the motor increases.

10 When the controller drum is turned farther in the paying-out direction the contactors 64 and 66 are brought into contact with the contactors 28^a and 28^b, respectively; the coil 64^b is energized and relay 64^c opens; the coil 66^b is energized and the relay 66^c opens, de-energizing the shunt field 4^c; interlock 67^c (mounted on the movable contactor of relay 66^c), closes; coils 67, 68 and 69 are energized; holding coil 70 is shorted and relay 67^a closes; holding coil 71 is shorted and 20 relay 68^a closes; holding coil 72 is shorted, and relay 69^a closes. The closing of relays 67^a, 68^a, and 69^a cuts the resistance elements 75, 74 and 73 out of circuit; the motor runs at high speed.

If, while the motor is turning slowly in the 25 paying-out direction, accelerating forces occur, due to the overhauling action, or increasing tension of the cable and tending to speed up the motor, said motor will, in resistance thereto, regenerate and operate as a dynamic brake; the 30 result being somewhat similar to that effected by an automobile engine turning ahead in low, or second gear and resisting acceleration by gravity of the speed of the car while moving down hill. But if the tension on the cable becomes sufficient 35 to move the controller to a higher speed, or higher electrical gear paying-out position, the speed of the motor will be accelerated and the tension of the cable will be temporarily eased.

In operation, however, the lever 31 is normally 40 locked in heaving-in position, thus temporarily swinging said link 25 on its pivoted connection with said link 24 and causing said links 25 and 26 to operate said controller lever thereby starting the winch to heave in until the strain on the cable rocks the brake wheel and brake far enough 45 to straighten said link 25 on its pivot 25^a thus returning said controller lever to neutral and stopping the motor. Under such circumstances, if the cable becomes slack, said spring 21 will 50 rock said band and wheel to their original positions, thus swinging said link 25 on its pivot 25^a to operative heaving-in position until such slack has been taken up.

If it is desired to arbitrarily slack the cable, 55 said lever 31 is temporarily set at the opposite, or pay-out side of center or vertical axis of said quadrant thus swinging the link 25 and valve or controller stem or lever into paying-out, or motor reversing position. When it is desired to stop such pay-out operation until the 60 cable has become taut again, said lever 31 may be set at center or neutral position, or again returned to a heave-in position.

When the lever 31 is set at center, or neutral, 65 and if there is no strain on the cable, one of said tongues, as 15, bears against a fixed shoulder or stop 34 of any suitable structure, preferably extending from, or forming part of said base and on the pay-out side of said tongue.

70 When it is not desired to use said winch, any suitable cut-off valve or switch may be arbitrarily operated to cut off the admission of energy creating means to said prime mover, as will be well known to the art.

A towing or mooring cable 35 is engaged by said drum.

While I have described one form of my said invention, it is obvious that various modifications thereof or alterations therein may be made within the scope and spirit of certain of my claims.

What I claim is—

1. The combination of a shaft, a cable drum journaled on said shaft, a brake wheel journaled on said shaft, a brake band mounted on said wheel, means for putting said band under tension, a prime mover, means connected to said brake band for automatically governing the admission of energy to said prime mover, means for transmitting motion from said prime mover to said shaft, and means for transmitting motion from said shaft to said drum and brake wheel. 85

2. The combination of a rotatable shaft, a cable drum journaled on said shaft, a brake wheel journaled on said shaft, a brake band mounted on said wheel, adjustable means for putting said band under tension, a prime mover, means connected to said brake band for automatically governing the admission of energizing fluid to said prime mover, means for transmitting motion from said prime mover to said shaft, and means for transmitting motion from said shaft to said drum. 95

3. The combination of a rotatable shaft, a cable drum journaled on said shaft, a brake wheel journaled on said shaft, a brake band mounted on said wheel, resilient means for putting said band under tension, a prime mover, means connected to said band for automatically governing the admission of energy to said prime mover, means connected to said automatic governing means for manually shifting a portion of the same to arbitrarily govern the admission of energy to said prime mover, means for transmitting motion from said prime mover to said shaft and means for transmitting motion from said shaft to said drum and brake wheel. 105

4. The combination of a rotatable shaft, a cable drum member journaled on said shaft, a brake wheel member journaled on said shaft, a brake band applied to said brake wheel, resilient means for putting said band under tension, a gear keyed to said shaft, one of said members being provided with a relatively stationary annular internal gear, the other of said members having a gear journaled thereon in mesh with said internal gear and said keyed gear, a prime mover, transmission means for transmitting motion from said prime mover to said shaft, and means connected to said brake band for automatically governing the admission of energizing fluid to said prime mover. 120

5. The combination of a shaft, a cable drum journaled on said shaft, a brake wheel member journaled on said shaft, a brake band member mounted on said wheel member, a prime mover, means for transmitting motion from said prime mover to said shaft, means for transmitting motion from said shaft to said cable drum and brake wheel, a throttle valve for said prime mover, and transmission means connected to one of said members and to said valve for operating said valve. 135

6. The combination of a rotatable shaft, a gear keyed to said shaft, a cable drum member journaled on said shaft, a brake wheel member journaled on said shaft, a brake band mounted on said wheel, resilient means for putting said band under tension, one of said members being provided with an annular internal gear, the other 145

- of said members having a gear journalled thereon in mesh with said internal gear and with said keyed gear, resilient means for resisting and limiting motion of said wheel and brake band, a prime mover, means for transmitting motion from said prime mover to said shaft, and means connected to said brake band for automatically governing the admission of energizing fluid to said prime mover. 80
- 10 7. The combination of a rotatable shaft, a cable drum journalled on said shaft, a brake wheel member journalled on said shaft, means for transmitting motion from said shaft to said drum, a friction brake member in contact with said wheel, resilient means for resisting and limiting the movement of one of members, a prime mover, gears for transmitting movement from said prime mover to said shaft, a throttle for said prime mover, and transmission means connected to one of said members and to said throttle for automatically operating said throttle. 85
- 15 8. The combination with a suitable support, of a rotatable shaft, a cable drum journalled on said shaft, a wheel member journalled on said shaft, a brake member applied to said wheel member, resilient means for pressing said brake member against said wheel member, a prime mover, transmission means connected to one of said members and to the controlling valve of said 90
- 20 prime mover, transmission means engaging said prime mover and said shaft, and transmission means engaging said shaft and drum and wheel member. 95
9. The combination with a suitable support, of a rotatable shaft, a drum journalled on said shaft, a wheel member axially alined with said drum, a brake applied to said wheel member, resilient means for pressing said brake against said wheel member, a prime mover provided with a controlling valve, transmission means engaging said prime mover and said shaft, transmission means engaging said wheel member and drum and shaft, a series of levers connected to one of said members and to said controlling valve, a lever connected to one of the levers of said series for arbitrarily shifting its position, and resilient means for resisting rocking movement in one direction of said wheel and wheel brake. 100
- 25 10. The combination of a support, a shaft journalled on said support, a drum journalled on said shaft, a prime mover provided with a controlling valve, transmission means engaging said prime mover and said shaft, a wheel member axially alined with said shaft, transmission 105
- 30 means engaging said wheel member and drum and shaft, a brake for said prime mover, a brake member for said wheel member, transmission means engaged by one of said members and adapted to operate said valve, and a lever connected to said valve-operating transmission means for arbitrarily adjusting the same. 110
- 35 11. The combination with a rotatable member, of a rotatable shaft, a gear mounted on said shaft and adapted to turn the same, a prime mover, transmission means engaged by said prime mover and engaging said gear, an internal gear journalled on said shaft, a sun gear mounted on said shaft and adapted to be turned thereby, a planetary gear carried by said rotatable member and engaging said sun gear and said internal gear, resilient means adapted to resist the movement of said internal gear, in one direction, a valve adapted to govern the admission of energizing means to said prime mover, transmission means governed by said internal gear and adapted to operate said valve, and means for adjusting such valve operating transmission means. 115
- 40 12. The combination with a rotatable member, of a rotatable shaft, a prime mover, transmission means engaged by said prime mover and by said shaft for turning said shaft, an oscillatable member journalled on said shaft, a sun gear mounted on said shaft and adapted to be turned thereby, a planetary gear carried by one of said members 120
- 45 and engaging said sun gear, the other of said members having an annular gear portion adapted to engage said planetary gear, yielding means adapted to resist the movement in a rotarial direction of one of said members, a valve for controlling the admission of energizing means to said prime mover, transmission means adapted to be actuated by one of said members and adapted to operate said valve, and means for adjusting such valve operating means. 125
- 50 13. The combination with a rotary member, of a rotatable shaft, a prime mover, transmission means engaged by said prime mover and by said shaft for turning said shaft, an oscillatable member journalled on said shaft, a sun gear mounted on said shaft and adapted to be turned thereby, a planetary gear carried by one of said members 130
- 55 and adapted to engage said sun gear, the other of said members having an annular gear portion adapted to engage said planetary gear, and yielding means adapted to resist the movement in a rotary direction of one of said members. 135
